UNITED STATES PATENT OFFICE.

FREDERICK HENRY ROYCE, OF WEST WITTERING, NEAR CHICHESTER, ENGLAND, AS-
SIGNOR TO ROLLS-ROYCE LIMITED, OF NIGHTINGALE ROAD, DERBY, ENGLAND.

IGNITION APPARATUS FOR INTERNAL-COMBUSTION ENGINES.

Application filed October 27, 1925, Serial No. 65,259, and in Great Britain November 17, 1924.

This invention relates to improvements in apparatus for automatically controlling the timing of cylinders of internal combustion engines. More specifically, it is designed as 5 an improvement in apparatus of the type disclosed in my United States Patent 1,163,692, December 14, 1915, in which a speed responsive device controls a relay valve to introduce 10 a source of energy, independent of such device, for operating the spark control.

One of the main objects of the present invention is therefore to increase the sensitivity of apparatus of this type by decreasing as much as possible the resistance offered by 15 the relay valve to movement by the speed responsive device, and to transfer the operation of spark as much as possible to the relayed source of operating energy.

Another object of the invention is to connect the spark control to the automatic relay by a linkage which is adapted for manual operation independently of its automatic operation by the relay.

Other objects of the invention will become 25 apparent as the detailed description of the apparatus proceeds.

In the drawings:—

Fig. 1 is a view showing in central vertical section, the speed responsive relay mechanism 30 of the invention connected up to the spark control linkage, shown partly broken away and in elevation;

Fig. 2 is a plan of the apparatus shown in Fig. 1;

Fig. 3 is fragmentary plan view of the linkage shown in Fig. 1;

Figs. 4 and 5 are similar plan views of said linkage, with the parts thereof shown in different operative positions;

Fig. 6 is a vertical section on the line 6—6 of Figure 3; and,

Fig. 7, is a vertical section on the line 7—7 of Figure 3.

Referring to Fig. 1, the numeral 1 designates a casing in which a shaft 2 is journaled in suitable bearings 3 and 4 to be rotated in accordance with the engine speed by any suitable means such as the worm gearing designated generally by numeral 5.

The weighted arms 6 of a speed responsive governor of any suitable type are pivoted on shaft 2 to rotate therewith in the usual manner, and links 7 connect these weights to a sleeve *a* mounted to slide and rotate on shaft 2.

A lever *L* fulcrumed on the pin *a*² fixed to 55 the casing 1 has the free end of its shorter arm *a*⁰ pivoted to the sleeve *a*, and has the free end of its long arm *a*¹ pivoted to the end of rod *d*¹ to control the operation of the balanced relay valve, reciprocable in the casing *b* fixed in any suitable manner to the casing 60 1.

The casing *b* has its lower end projected and machined to form a cylinder *b*¹ provided with a row of apertures *b*¹¹ in its periphery about half way between the top and bottom thereof. A cylindrical member *b*² having a pipe fitting *b*²² extending radially therefrom and of larger internal diameter than the external diameter of cylinder *b*¹ is detachably 70 clamped to the casing *b*, concentrically with cylinder *b*¹, by means of the cup *b*³ screw-threaded onto the lower end of the cylinder *b*¹ any suitable gaskets *g* and *g*¹ being interposed between the adjacent ends of casing *b* 75 member *b*² and cup *b*³, respectively, to ensure proper liquid tight fit between these parts.

In the cylindrical space *b*⁴ between cylinder *b*¹ and member *b*² there is clamped the filtering screen *b*⁴⁴, to trap any sediment or 80 other matter, in the oil forced through pipe 22 from the lubricating system, which might tend to prevent proper operation of the sleeve piston *c* which is reciprocably mounted in the cylinder *b*¹.

The piston *c* is expanded at its upper end to form a piston head *x* of larger diameter than piston *c* and slidably in cylinder *y* of the same diameter formed in the casing *b*. This piston head *x* forms with the bottom of cylinder *y* a stop to limit the downward movement of the piston *c*. The piston *c* is provided with a row of apertures *c*¹ adapted to align with the apertures *b*¹¹ in cylinder *b* when the piston is in its lowest position; and is also 90 provided in the expanded head *x* with rows of apertures *c*² and *c*³, the apertures *c*² communicating with the dished out part *b*⁵ of piston head 4, and the apertures *c*³ terminating at their upper ends in the annular space *c*⁴. A 100 cylindrical recess *c*⁵ is formed in the periphery of piston *c* and of a length sufficient to establish communication between the apertures *b*¹¹ and *c*¹ throughout the entire range of movement of the piston *c* in the cylinder 105 *b*¹. A leather oil tight ring *c*⁶ is secured to said head *x* by means of the metal plate *c*⁷ and locknut *c*⁸.

In order to effect lifting movement of piston *c*, the latter is formed as a cylinder within which a cylindrical member *d* is slidably mounted and is connected at its bottom by a universal joint to a rod *d*¹ having its upper end pivoted to the free end of the lever arm *a*¹ of the speed responsive apparatus. The member *d* is designed for limited sliding movement in the piston *c* and is provided with a cylindrical recess in its periphery of sufficient length to maintain it constantly in communication with row of apertures *c*¹ in piston *c*. The universal joint end of member *d* is also provided with a row of apertures *d*⁴ to permit the escape of any oil that might overflow from aperture *c*¹ under certain conditions of relative movement between piston *c* and member *d*.

Resting on top of the piston head *x* is a cylindrical piston *e* slidable in a cylinder *e*¹ formed in a cap of casing *b*, the piston *e* and cylinder *e*¹ being provided with aligned slots *e*¹¹ and *e*¹¹¹ to receive the arm *a*¹ of the speed responsive apparatus. The piston *e* is provided with diaphragms *e*² and *e*³ spaced apart to receive between them an arm *f* fixed to the shaft *f*¹ journaled in the cap *f*² of casing *b* which is suitably bolted or otherwise secured to casing *b*.

The cylinder *e*¹ is closed at its upper end by a screwthreaded plug *f*³, and between this plug *f*³ and the diaphragm *e*² there is arranged a spiral compression spring *g* which resists the upward movements of piston *e* and returns it to its lowest initial position when the oil pressure is removed.

The shaft *f*¹ extends through its journal *f*² and has secured to the projecting end thereof, the lever arm *f*⁴ which, with shaft *f*¹ and the arm *f* constitutes a bell crank lever controlling the operating linkage of the spark control.

The operation of the apparatus so far described is somewhat as follows: When the engine starts the sleeve *a* is drawn downwardly by the centrifugal governor mechanism in accordance with the speed of the engine. This movement, through arms *a*⁰, *a*¹ and rod *d*⁴ raises the member *d* until its recess *d*³ communicates with the aperture *c*². So long as recess *d*³ communicates with aperture *c*², oil under pressure from the lubricating system is forced into the dished out recess *b*⁵ (through pipe *b*²², apertures *b*¹¹, *c*¹, recess *d*³, and aperture *c*²) and, acting under expanded head *x* raises the piston *e* against resistance of spring *g* to rotate bell crank arm *f*, and thereby operate the spark control linkage.

It will be apparent from the drawing that the piston *c* closely follows the movement of the member *d* because, as the member *d* rises under the influence of the centrifugal device, it opens the ports *c*² and thereupon the piston *c* under the influence of oil pressure device is raised, till by such movement the ports *c*² are

again closed; while on the other hand if the member *d* (under the influence of the centrifugal device when the speed decreases) descends, the ports *c*² are opened and thereupon under the influence of spring *g* (the oil pressure having been released) the piston *c* descends until by such movement the ports *c*² are closed again. The piston *c* therefore follows the member *d*, both in its upward and downward movement, but is actuated wholly by oil pressure, while the member *d* is subjected to no unbalanced axial pressure whatever, and therefore relieves the centrifugal device from any load incidental to the operation of the spark controlled mechanism.

The spring *s* is necessarily designed so that when the ports *c*² are open it yields before the oil pressure, but when the ports *c*² are open it forces the piston *c* downwards.

The exhaust oil emanating from ports *c*⁴ when the speed of the engine is decreasing (necessarily a constantly recurring event) falls down the hollow member *d* and passes through the holes *d*⁴ until the cap *b*³ and the hollow member *d* are full of oil, and thenceforth the exhaust oil overflows the top of the piston *c* and falls into the sump, the cap *b*³ and member *d* remaining always full of oil.

As will be obvious from the drawing, all axial and other pressure on the valve *d* due to oil pressure and tending to resist movement thereof in its cylinder, are eliminated or balanced by causing the oil to enter the cylinder walls radially and arranging the cylindrical recesses *d*³ symmetrically around the periphery of the member *d*.

As will be obvious from the drawing, all axial pressure on the valve *d* tending to resist movements thereof in its cylinder are eliminated by causing the oil to enter the cylinder walls radially, and arranging the cylindrical recesses *d*³ and *c*⁵ relative to the oil passages so that the axial pressure exerted at one end of each recess is counterbalanced by the pressure at the other end thereof.

Referring to Figs. 3 to 7, inclusive, *h* designates a bracket bolted to any suitable part of the engine or chassis to support a tubular member *h*¹ having the spindle *h*² mounted to rotate in bearings *h*³ therein. The lever *h*⁴, having two apertured bosses at one end thereof, is secured by its boss *h*⁵ to the end of spindle *h*², and a pin *h*⁶ is fixedly secured in the other apertured boss *h*⁵⁵.

Two brackets *i* similarly bolted to any suitable part of the engine or chassis carry a tubular member *i*¹ in which the spindle *i*² is mounted to rotate in the bearings *i*³. The lever *i*⁴ having two apertured bosses *i*⁵ and *i*⁵⁵ at one end thereof, is secured by its boss *i*⁵ to the projecting end of the pin *i*², and a pivot pin *i*⁶ has its lower end fixed in the other apertured boss *i*⁵⁵.

The levers *j* and *k*, normally parallel to

each other, are centrally fulcrumed to rotate on pivots h^6 and i^6 , respectively. One end of lever j is pivotally connected to the end of a rod j^1 which is operably connected to the 5 magneto advance and retard device; and one end of the arm k is pivotally connected to the end of a rod k^1 operably connected to the battery advance and retard device. The other ends of the levers j and k are pivotally 10 connected to each other by the link l . A link l^1 has one end pivotally connected to the pivot connecting the end link l to lever k , and has its other end connected by a universal joint to the free end of the arm f^4 of the speed 15 responsive relay.

A hand operated lever m is pivotally connected to the free end of the lever i^4 , and a link n pivotally connects the free end of lever h^4 with the end of a lever i^{44} which with 20 lever i^4 forms a bell crank fixed to the projecting end of the spindle i^2 .

It will be evident from Figures 3, 4, and 5, that the hand control m operates by moving the fulcrums h^6 and i^6 about their fixed pivot pins h^2 and i^2 , without disturbing the position of the link l , which is therefore controlled, as to position, by the centrifugal oil pressure device alone. It therefore results 25 that each control superimposes its effect on 30 that of the other.

In the examples shown with the controls set as in Fig. 3, the magneto ignition occurs 12° before top dead center and the battery ignition 10° after top dead centre, a gap of 22° 35 occurring, consequently, between the two. When the hand control is moved to the position shown in Fig. 4, both ignitions occur 20° before top dead centre. Thus the magneto 40 is only advanced 8° but the battery is advanced 30° , this inequality being secured by arranging that the spindle h^6 is displaced a minimum amount laterally, while spindle i^6 is displaced a maximum amount. In the 45 position shown in Fig. 5, both ignitions occur 50° before top dead centre. The operation of the controls by the automatic device always moves both ignitions a like amount (which is 50 30° maximum) and the ignitions become synchronized as soon as the hand control is advanced from full retard position through about half its total range.

I claim:—

1. The combination with an internal combustion engine having a pressure feed lubricating system, and a timing device, of a casing having a cylinder formed therein and having a second cylinder of smaller diameter than the first projecting concentrically with the first from the bottom of said casing and 55 having a row of radial apertures in the periphery thereof, a fitting for conducting lubricant under pressure from said system radially into said second cylinder through said 60 apertures, a cylindrical piston slideable in the second cylinder and having a dished head 65

slidably fitting the first cylinder, the piston being provided with passageways in constant fluid conducting communication with said apertures and the head thereof being provided with holes for the passage of fluid 70 from said passageways into and out of the dished part of said head, a valve slideable in said piston to control the flow of fluid through said holes, and means operatively connecting said head to said timing device. 75

2. The combination with an internal combustion engine having a pressure feed lubricating system, and a timing device, of a cylinder, means for conducting fluid from said system radially into said cylinder, a cylindrical piston reciprocable in said cylinder by the action of said fluid thereon, a valve slideable in said piston to control the reciprocation of said piston by said fluid, a support for said cylinder, a lever fulcrumed on said support and having one end thereof pivotally connected to said valve, means responsive to the engine speed for rocking said lever about its fulcrum and spring controlled means operatively connecting said piston to said timing device. 80

3. Timing apparatus including a cylinder provided with radial apertures, a cylindrical piston provided with apertures registrable with the first named apertures, reciprocable 95 therein, fluid under pressure entering said cylinder radially and operating axially on said piston to control the operation of the latter, a valve reciprocable in said piston to control the operation of said fluid thereon 100 and having a cylindrical fluid receiving recess shaped to balance the pressure thereon of said fluid in all directions, and means for reciprocating said valve. 105

4. The combination with an internal combustion engine provided with two ignition systems having spark timing devices therein, a member variably movable in response to the speed of the engine, and a linkage pivotally and nonslidably connecting said member to 110 said devices to control the movements thereof simultaneously.

5. The combination with the apparatus set forth in claim 4, of a second linkage pivotally connected to the first named linkage and 115 manually operable to move parts of the first named linkage independently of said member to control said devices simultaneously and independently of said member.

6. The combination with the apparatus set forth in claim 4, of a manually controlled linkage pivotally connected to the first named linkage, and operable independently of said member to move the parts of the first named linkage connected directly to said devices simultaneously and relative to each other. 120

7. In combination with an internal combustion engine having a fluid pressure feed lubricating system and a timing device, a cylinder, means for conducting oil from said 130

system radially only into said cylinder, a piston reciprocable in said cylinder in response to pressure of the oil thereon and being provided with supply and exhaust ports for the oil acting thereon, valve mechanism controlling the flow of oil through said ports, speed responsive means operated by said en-

gine to control the operation of said mechanism, and means for connecting said piston operably with said device.

10

In witness whereof I have signed this specification.

FREDERICK HENRY ROYCE.
